Patented Sept. 1, 1925.

UNITED STATES PATENT OFFICE.

JAMES S. THOMPSON, OF PELHAM, NEW YORK.

MOLD FOR MAKING CASTINGS.

Application filed July 21, 1924. Serial No. 727,100.

To all whom it may concern:

Be it known that I, JAMES S. THOMPSON, a citizen of the United States, residing at Pelham, in the county of Westchester and State of New York, have invented certain new and useful Improvements in Molds for Making Castings, of which the following is a specification.

The object of this invention is to improve and facilitate the manufacture of castings in permanent molds by venting the mold in a novel manner to permit the escape of gases during the casting operation.

Another object of the invention is to dispose of vent openings in a manner which will permit the free escape of gases, but which will prevent the flow of molten metal thereinto under any ordinary conditions of casting.

And a further object of the invention is to construct the vent openings in a manner which will avoid damage to the mold or to the casting, or interfere with the opening of the mold in event that the metal should run into the venting opening.

The objects of the invention will be more particularly pointed out hereinafter in connection with the detail description thereof in these specifications. The invention is especially adapted for and useful in connection with the manufacture of brake shoes, and for that reason I have selected this embodiment for illustration in the accompanying drawings, referring to which

Fig. 1 is a longitudinal sectional view of a brake shoe mold wherein the mold cavity is faced with refractory material.

Fig. 2 is a transverse sectional view on the line 2-2 of Fig. 1.

Fig. 3 is a longitudinal sectional view of a metal mold.

Fig. 4 is a transverse sectional view on the line 4-4 of Fig. 3.

Referring to the drawings, the mold comprises a drag 5 and a cope 6 having a mold cavity 7 and a pouring gate 8. In Figs. 1 and 2 the mold cavity has a facing of refractory material 9, which is shown in a form found to be satisfactory for this purpose; but I do not wish to be understood as limiting or restricting my invention to this or any other style of mold or to this or any other particular construction and arrangement of refractory material, because it will be apparent as the invention is better understood that it can be embodied in a variety of

molds for making a great many different castings. I have simply selected these types for illustration and to enable my invention to be readily understood.

A reinforcing back 10 with an attaching lug 11 supported in proper relation to the back by a sand core 12 may be secured in proper position in the mold cavity for embedding in the shoe by any suitable means; and as one means which may be satisfactorily employed I have shown a wire device having a hooked end 13 to engage the back, and a deformed shank 14 which is arranged in an opening 15 in the cope and frictionally engages the wall of the opening to hold the back unit in place in the mold cavity. I preferably employ two of these holding devices, as shown in Fig. 1.

I provide in the cope a vent opening 16 which extends from the top of the lug through the top of the cope, and I also provide one or more vent openings 17 which extend from the top of the reinforcing back through the top of the cope. These openings taper from their inner ends to their outer ends, being larger at their inner ends, as shown. For some castings more vent openings will be desirable than for others, and this is also true with respect to the molds and will be determined largely by practical experience. I have found, however, that when a part of the insert, either the reinforcing back or the lug, covers the inner end of the vent opening, the gases will escape through the opening but the metal will not run into said opening. In the manufacture of brake shoes it has been found that when the back unit is properly supported in the mold, the metal will not run over the back and if the back covers the opening there is little, if any, chance that the metal will ever run into the opening. If a back unit should accidentally become misplaced from its proper position in the mold cavity, the metal may have a chance to run into the vent opening, and to prevent any unfortunate results in the way of injury to the mold or to the shoe if this should happen, I taper the vent openings as shown so that if the metal does run up into the vent opening, it will easily pull out of the opening when the mold is open or the casting is removed from the cope.

In Fig. 3 I have shown a metal mold without the refractory facing, but with a refractory plug 18 located in an opening 19

in the cope, and shaped to receive the back unit, as shown. In this construction the vent openings 17' extend through the refractory plug.

5. It will be understood that the vent opening may be placed at any convenient or desirable location where the inner end thereof will be covered, but preferably the vent opening is located at the highest point of 10 the mold cavity. In molds for making large castings, it is desirable to provide additional vent openings to prevent the formation of blow-holes or pockets in the casting. The number and location of the vent openings 15 will, as before stated, depend upon different conditions, and when the invention is understood by those skilled in the art the proper location of the vent openings will not involve any material difficulties.
20. I have found it desirable to locate the large inner end of the vent opening where it will be covered by the insert to be embedded in the casting, because I have found this a safe practice which will avoid the 25 flow of metal into the vent opening under usual casting conditions; but where the inner end of the vent opening can be located at or about a level with the pouring gate it will not be necessary that the vent opening 30 should be covered because there will be little chance of metal flowing into the vent opening, and if any does flow therein it will not become locked in the opening, but will freely pull out when the mold is opened 35 or when the casting is removed from the cope. Therefore, it will be understood that while it may be more satisfactory to have the inner end of the vent opening covered, I do not deem it absolutely essential in all 40 cases, and I believe this will be readily understood by those skilled in the art.
- I have shown and described the cope as 45 provided with openings 15 to receive the devices 14 for holding in place in the mold cavity the insert to be embedded in the casting, these openings being separate and apart from the vent openings, but in many molds it may be found convenient to combine these 50 openings in the form of a vent opening, in which case it would be desirable to enlarge the vent opening sufficient to compensate for the obstruction afforded by the holding device so that a sufficient vent would be provided in actual use.
55. I do not wish to be understood as limiting or restricting the invention to molds of any kind, size or shape, because it will be readily understood that the invention may be used in any mold to which it is or 60 may be adapted, and therefore I consider myself entitled to make all such changes in the form, construction, location and arrangement of the invention, as fairly fall in the accompanying claims.

65. I claim:—

1. A permanent mold for making castings comprising a drag and a cope, said cope having a continuous opening extending therethrough for venting the mold cavity and larger at its inner end than at its outer end. 70
2. A permanent mold for making castings comprising a drag and a cope, said cope having an opening therein, and a refractory plug in said opening, said plug having a 75 vent opening extending therethrough.
3. A permanent mold for making castings comprising a drag and a cope, said cope having an opening therein, and a refractory plug in said opening, said plug 80 having a vent opening extending therethrough and larger at its inner end than at its outer end.
4. A permanent mold for making castings comprising a drag and a cope having 85 a mold cavity therein, and an insert arranged in said mold cavity for embedment in the casting, said cope having a vent opening extending therethrough whose inner end is covered by said insert. 90
5. In a permanent mold for making castings, the combination of a drag and a cope having a mold cavity therein, said cope having a vent opening extending therethrough, an insert arranged in said mold 95 cavity over the inner end of said vent opening for embedment in the casting, and means for holding the insert in the mold. 100
6. In a permanent mold for casting brake shoes, the combination of a drag and a cope, an insert comprising a lug for embedment in the casting, and means for holding the insert in proper position in the mold cavity, said cope having a vent opening therein whose inner end is covered by said lug. 105
7. In a permanent mold for casting brake shoes, the combination of a drag and a cope, an insert comprising a reinforcing back for embedment in the casting, and means for holding the insert in proper position in the 110 mold cavity, said mold having a vent opening therein whose inner end is covered by said reinforcing back. 115
8. In a permanent mold for casting brake shoes, the combination of a drag and a cope having a mold cavity therein, an insert for embedment in the casting and comprising a reinforcing back and an attaching lug, and means for holding said insert in the mold cavity, said cope having vent openings extending therethrough whose inner ends are 120 covered by said back and lug. 125
9. A permanent mold for making castings having a mold cavity therein and a tapering opening for venting the mold cavity and extending from the mold cavity to an outer wall of the mold and larger at its inner end than at its outer end. 130

JAMES S. THOMPSON.
